TIRE

William F. Billingsley, Silver Lake, Ohio, assignor to The B. F. Goodrich Company, New York, N. Y., a corporation of New York

Application January 25, 1955, Serial No. 34,197

Term of patent 14 years

(Cl. D90—20)

Fig. 1 is a perspective view of a tire showing my new design; it being understood that the full line portion of the drawing is repeated throughout the circumference of the tire disclosed by means of dotted lines.

Fig. 2 is a fragmentary view thereof drawn to an enlarged scale; and

Fig. 3 is a section through the tire taken on line 3—3 of Fig. 2.

The dominant features of my design reside in those portions shown in solid lines.

I claim:

The ornamental design for a tire, as shown and described.
